UNITED STATES PATENT OFFICE.

JOHN MERKEL, OF ROBINSON, NORTH DAKOTA.

VENTILATOR.

1,310,537.

Specification of Letters Patent. Patented July 22, 1919.

Application filed July 18, 1918. Serial No. 245,543.

To all whom it may concern:

Be it known that I, JOHN MERKEL, citizen of the United States of America, residing at Robinson, in the county of Kidder and State 5 of North Dakota, have invented certain new and useful Improvements in Ventilators, of which the following is a specification, reference being had therein to the accompanying drawing.

10 This invention relates to a ventilator and has for its principal object the production of a ventilator which will allow the air to slowly pass therethrough.

Another object of this invention is the 15 production of means whereby the ventilator may be lengthened so as to fit different thicknesses of walls.

Another object of this invention is the 20 production of simple and efficient shaft brackets.

A still further object of this invention is the production of means upon the outer end of the ventilator for preventing flies, etc., from going through the ventilator and upon 25 the inner end to provide means for closing said ventilator altogether.

With these and other objects in view, this invention consists of certain novel combinations, constructions and arrangements 30 of parts as will be hereinafter fully described and claimed.

In the accompanying drawings:

Figure 1 is a vertical section taken 35 through the ventilator showing the same in a wall.

Fig. 2 is a side elevation of the device showing the same in a wall.

Fig. 3 is an end view of the ventilator with the screening detached.

40 Fig. 4 is a detail perspective view of the shaft bracket.

Fig. 5 is a view of the outer end of the ventilator.

By referring to the accompanying drawing 45 by numerals, it will be seen that 1 designates a wall into which is fitted the ventilator. This ventilator is provided with a drum 2 which drum is provided with the neck portion 3 upon which neck portion 3 is 50 mounted the door 4 by means of the hinge 5. This door 4 is hingedly mounted upon the end inside the room and has for its object to close or open the ventilator as desired.

Upon the outer end of the ventilator is 55 provided the screening 6 which is held in

place by means of the band 7 and the sleeve 8, this sleeve 8 being provided with the flange 9 which will fit snugly against the outer face 10 of the wall 1. It will be seen that if it is desired to lengthen the ventilator so 60 as to fit the small differences which are necessarily found in the ordinary walls, that the sleeve 8 and band 7 may be pushed outwardly, sufficiently so that the flange 9 will fit snugly against the outer face of the wall 65 10. Inside the drum 2 there is provided the shaft brackets 11 upon which is mounted the shaft 12 which carries the fan wheel 13. By referring especially to Fig. 4, it will be seen that the shaft bracket 11 is formed from 2 70 strips of metal, the inner strip 14 is provided with an aperture 15 and is bent at its ends so as to form the right angular wings 16. The outer strip 17 is bent intermediate its ends so as to form the pocket 18 and is 75 also bent at its ends so as to form the right angular wings 16. By referring especially to Figs. 1 and 2, it will be seen that these wings 16 extend flush with the outer ends of the drum 2 and will efficiently hold the bracket 80 in its proper position. These strips 14 and 17 are held together by means of a plurality of rivets 19.

The shaft 12 is adapted to pass through the aperture 15 and rest within the pocket 18 85 as is clearly shown in Fig. 1. Intermediate the end portions of this shaft 12 is carried the fan 13 which fan is formed from a single piece of sheet metal so as to have a circular periphery. The fan is cut along a plurality 90 of radially extending lines so as to form the blades 20. These blades 20, it will be seen, are twisted out of alinement with the hub portion 21 of the fan. This fan is held upon the shaft 12 by any suitable means such as 95 solder, etc.

From the above description, it will be seen that a ventilator has been produced which is provided upon its outer end with means for preventing the entrance of vermin 100 and upon its inner end with means for closing and opening the ventilator as desired. A ventilator has also been provided which has a fan rotatably carried therein so as to prevent the air from passing through the ventilator too quickly and means has been provided for efficiently holding this fan.

What is claimed as new is:

In a device of the class described, the combination with a drum, of a pair of sheet 110

metal brackets positioned in said drum, each bracket comprising an inner and an outer strip, the inner strip being apertured at its center, the outer strip provided with a pocket at its center positioned over the aperture of the inner strip, a shaft extending through the apertures of the inner strips of

the brackets and having its ends bearing against portions of the pockets formed on the outer strips, and a fan mounted upon said shaft.

In testimony whereof I hereunto affix my signature.

JOHN MERKEL.
